UNITED STATES PATENT OFFICE.

WILLIAM K. ANDREW, OF MILWAUKEE, WISCONSIN, ASSIGNOR TO INTERNATIONAL HARVESTER COMPANY, A CORPORATION OF NEW JERSEY.

STARTING MECHANISM FOR GAS-ENGINES.

No. 889,886.

Specification of Letters Patent.

Patented June 9, 1908.

Application filed December 11, 1907. Serial No. 405,981.

To all whom it may concern:

Be it known that I, WILLIAM K. ANDREW, a citizen of the United States, residing at Milwaukee, in the county of Milwaukee and 5 State of Wisconsin, have invented certain new and useful Improvements in Starting Mechanisms for Gas-Engines, of which the following is a specification.

My invention relates to gas engines, and 10 particularly to means for giving power impulses to the piston by means of compressed air admitted to the engine cylinder from any source of supply for the same; its object being to provide a mechanism that may be conveniently manipulated, and one that will be 15 effective for the purpose described. These objects are attained by the mechanism illustrated in the accompanying drawing, in which

20 Figure 1 represents a side elevation of the starting mechanism, secured to the base frame of an engine. Fig. 2 is an end view of Fig. 1. Fig. 3 is a sectional elevation of part of Fig. 1; and Fig. 4 is a cross section of Fig. 1 25 on line A—B.

Referring to the drawings, 1 represents a part of an engine base frame.

2 is a cam-shaft which may be operated from the engine by means of any of the well-known forms of mechanism, whereby the shaft is given one revolution for each two of the engine shaft, as is common in the construction of four cycle engines.

3 represents a rotary valve, secured to the 35 cam-shaft by means of a key 4, in a manner permitting it to move longitudinally along said shaft. The valve is preferably made slightly conical and, projecting beyond the end of the cam-shaft, is provided with an end 40 wall 5 inclosing the same.

6 represents an annular channel encircling the valve, which channel is provided with diametrically arranged openings 7 through its outer wall, and similarly arranged but 45 smaller openings 8 through its inner wall.

The valve is received by a casing 9, that is secured to the base frame by means of bolts 10, and 11 and 12 designate inlet and outlet ports therein, communicating with a source 50 of compressed air supply by means of a pipe connection 13, and with an engine cylinder by means of a pipe connection 14, respectively. The connections between pipe 14 and the cylinder may include any preferred 55 form of valve mechanism adapted to be ad-

justed in a manner to admit air from the starting mechanism, or gas from the mixing chamber to said cylinder at the will of the operator. A common form of valve 15 in pipe 13 controls the admission of compressed 60 air to the valve case, and a similar valve may be used in pipe 14 if desired.

The valve casing is provided with an exhaust channel 16, having one end communicating with the pipe 14 and its opposite end 65 forming a port 17 adapted to communicate with the annular channel 6 in the valve, which port is arranged at an angle of 90 degrees with the inlet and outlet ports 11 and 12; and 18 represents an exhaust port through 70 said casing communicating with the atmosphere by means of pipe 19, which port is arranged diametrically opposite the port 17. The cam-shaft is provided with a transverse opening 20 that communicates with the annular channel 6 by means of small ports 8 through the inner wall of the valve, and an axial opening 22 leading from said transverse opening to a small chamber 23, between the end of the shaft and the end wall 5 of the 80 valve.

A cap 24 is secured to the valve casing, and 25 designates a bolt received by said cap and provided with a conical head 26 adapted to contact with the wall 5, and, passing through 85 an opening in the cap, is provided with a nut 27 at its outer end.

28 designates a spring surrounding the bolt and operative to press it against the end wall 90 of the valve.

29 designates a plate interposed between the nut 27 and the cap and adapted to be rotated thereon, and 30 designates face cams formed on the cap 24, which cams are adapted to engage with other opposing similar 95 cams 31 forming a part of plate 29, in a manner to cause said plate to move outward and disengage the bolt from the valve.

Secured to the stem of the valve 15 is a lever 32 that overhangs the valve casing, and 100 33 designates a laterally projecting stud secured to said lever and adapted to engage with a notch 34 formed in the periphery of the plate 29 in a manner to cause said plate to rotate when said lever is moved for the 105 purpose of opening or closing the air admission valve 15.

The mechanism operates in the following manner to start the engine: With the piston in position to begin its power stroke, the air ad- 110

mission valve is opened by means of the lever, which lever in its movement will rotate plate 29, and the opposing cam surfaces on said plate and cap 24 will cause the plate to move 5 against nut 27 and disengage bolt 25 from contact with the rotary valve; and the pressure of the air flowing from the annular channel in the valve through the openings in the cam-shaft into chamber 23 will cause the 10 valve to be closely seated in the casing; it being understood that the rotation of the rotary valve is so timed by means of its connection with the cam shaft as to open the air inlet and outlet ports 11 and 12 when the piston 15 is in position to begin its power stroke, and the air flowing into the engine cylinder propels the piston during such stroke, and the exhaust ports being opened at the end of the power stroke, the air charge is exhausted, 20 and by the rotation of the valve the engine continues to operate as a compressed air engine until the operator, by means of the lever 32, closes the admission valve, which operation turns the plate 29 in a manner to release 25 the spring pressed bolt 25, which will then contact with the valve in a manner to slide it through the valve casing and separate it from its seat therein.

What I claim as my invention, and desire 30 to secure by Letters Patent, is:

1. A starting mechanism for gas engines comprising, in combination, a cam shaft, a rotary valve connected with said cam shaft in a manner to be rotated therewith, a valve 35 casing having said valve mounted therein, said casing having inlet and outlet ports communicating with a source of compressed air supply and an engine cylinder, respectively, and inlet and outlet exhaust ports 40 communicating with the engine cylinder and atmosphere, respectively, said rotary valve having a channel that communicates with said air and exhaust ports alternately.

2. A starting mechanism for gas engines 45 comprising, in combination, a cam shaft, a rotary, conical valve secured to said shaft in a manner to rotate therewith and be longitudinally movable thereon, a valve casing having 50 said valve mounted therein, said casing having inlet and outlet ports communicating with a source of compressed air supply and an engine cylinder, respectively, and inlet and outlet exhaust ports communicating with the engine cylinder and atmosphere, respectively, said rotary valve having a channel 55 that communicates with said air and exhaust ports alternately, and means communicating with said air supply and operative to move said valve longitudinally relative to 60 said casing.

3. A starting mechanism for gas engines 65 comprising, in combination, a cam shaft, a rotary, conical valve keyed to said shaft in a manner to rotate therewith and be longitudinally movable thereon, said valve inclosing

the end of said cam shaft, a fixed valve casing having said valve mounted therein, said casing having inlet and outlet ports communicating with a source of compressed air supply and an engine cylinder, respectively, and inlet and outlet exhaust ports communicating with the engine cylinder and atmosphere, respectively, said rotary valve having an annular channel that communicates with said air and exhaust ports alternately, said cam shaft having an opening therein that permits air to flow from said channel against said valve in a manner to press it closely into said valve casing.

4. A starting mechanism for gas engines comprising, in combination, an engine frame, a cam shaft mounted in bearings upon said frame, a rotary, conical valve keyed to said shaft in a manner to rotate therewith and be longitudinally movable thereon, the smaller 80 end of said valve extending beyond the end of said shaft and inclosing the same, a valve casing secured to said frame and having said valve mounted therein, said casing having inlet and outlet ports communicating with a 85 source of compressed air supply and the engine cylinder, respectively, and inlet and outlet exhaust ports communicating with the engine cylinder and atmosphere, respectively, said valve having an annular channel 90 that communicates with said air and exhaust ports alternately, a cap secured to said valve casing, a spring mounted in said cap and operative against the smaller end of said valve in a manner to move the same from its 95 seat in said casing.

5. A starting mechanism for gas engines comprising, in combination, an engine frame, a cam shaft mounted in bearings upon said frame, a rotary, conical valve keyed to said shaft in a manner to rotate therewith and be longitudinally movable thereon, the smaller 100 end of said valve extending beyond the end of said shaft and inclosing the same, a valve casing secured to said frame and having said valve mounted therein, said casing having inlet and outlet ports communicating with a source of compressed air supply and the engine cylinder, respectively, and inlet and outlet exhaust ports communicating with the engine cylinder and atmosphere, respectively, said valve having an annular channel 105 that communicates with said air and exhaust ports alternately, a cap secured to said valve casing, a spring pressed bolt mounted in said cap and operative against the smaller end of said valve in a manner to move the same from its 110 seat in said casing, and means for withdrawing said bolt from contact with said valve.

6. A starting mechanism for gas engines comprising, in combination, an engine frame, a cam shaft mounted in bearings upon said frame, a rotary, conical valve keyed to said shaft in a manner to rotate therewith and be 115

- longitudinally movable thereon, the smaller end of said valve extending beyond the end of said shaft and inclosing the same, a valve casing secured to said frame and having said 5 valve mounted therein, said casing having inlet and outlet ports communicating with a source of compressed air supply and the engine cylinder, respectively, and inlet and outlet ports communicating with the engine 10 cylinder and atmosphere, respectively, said valve having an annular channel that communicates with said air and exhaust ports alternately, a cap secured to said valve casing, a spring pressed bolt mounted in said 15 cap and operative against the smaller end of said valve in a manner to move the same from its seat in said casing, and means for withdrawing said bolt from contact with said valve, said means comprising face cams forming part of 20 said cap, a plate rotatably mounted upon said cap and operatively connected with said spring pressed bolt, said plate having opposing face cams adapted to engage with the cams on said cap, and means for rotating said plate.
7. A starting mechanism for gas engines comprising, in combination, an engine frame, a cam shaft mounted in bearings upon said frame, a rotary, conical valve keyed to said 30 shaft in a manner to rotate therewith and be longitudinally movable thereon, the smaller end of said valve extending beyond the end of said shaft and inclosing the same, a valve casing secured to said frame and having said 35 valve mounted therein, said casing having inlet and outlet ports communicating with a source of compressed air supply and the engine cylinder, respectively, a connection from the source of air supply with said air 40 inlet comprising an admission valve, inlet and outlet exhaust ports communicating with the engine cylinder and atmosphere, respectively, said rotary valve having an annular channel that communicates with said 45 air and exhaust ports alternately, a cap secured to said valve casing, a spring-pressed bolt mounted in said cap and operative
- against the smaller end of said rotary valve in a manner to move the same from its seat in said casing, and means for withdrawing 50 said bolt from contact with said valve, said means being controlled by a lever connected with said air admission valve.
8. A starting mechanism for gas engines comprising, in combination, an engine frame, 55 a cam shaft mounted in bearings upon said frame, a rotary, conical valve keyed to said shaft in a manner to rotate therewith and be longitudinally movable thereon, the smaller end of said valve extending beyond the end 60 of said shaft and inclosing the same, a valve casing secured to said frame and having said rotary valve mounted therein, said casing having inlet and outlet ports communicating with a source of compressed air supply and 65 the engine cylinder, respectively, a connection from the source of air supply with said air inlet comprising an admission valve, inlet and outlet exhaust ports communicating with the engine cylinder and atmosphere, 70 respectively, said rotary valve having an annular channel that communicates with said air and exhaust ports alternately, a cap secured to said valve casing, a spring pressed bolt mounted in said cap and operative 75 against the smaller end of said rotary valve in a manner to move the same from its seat in said casing, and means for withdrawing said bolt from contact with said valve, said means comprising face cams forming part of 80 said cap, a plate rotatably mounted upon said cap and operatively connected with said spring pressed bolt, said plate having opposing face cams adapted to engage with the cams on said cap, said plate having a notch 85 in its periphery, a lever adapted to control said air admission valve, and a stud secured to said lever and adapted to engage with the notch in said plate.
